UNITED STATES PATENT OFFICE.

JAMES EDGAR BORDEN, OF PORTSMOUTH, NEW HAMPSHIRE.

IMPELLING MECHANISM.

Application filed June 17, 1924. Serial No. 720,567.

To all whom it may concern:

Be it known that I, JAMES EDGAR BORDEN, a citizen of the United States, residing at Portsmouth, in the county of Rockingham 5 and State of New Hampshire, have invented new and useful Improvements in Impelling Mechanism, of which the following is a specification.

The object of this invention is to provide 10 an impelling mechanism adapted to be used either as a rotary pump, driven by a prime motor to force water, or other fluid, through a conduit, or as a rotary engine or motor driven by a fluid under pressure.

15 The invention is embodied in the improved impelling mechanism, and in the various structural parts thereof, hereinafter described and claimed.

Of the accompanying drawings forming 20 a part of this specification.

Figure 1 is a side view, partly in elevation and partly in vertical section, of an impelling mechanism embodying the invention.

Figure 1^a is a fragmentary section on a 25 reduced scale.

Figure 2 is a fragmentary section, showing one end of the casing, and a fluid-directing plate therein.

Figure 3 is a perspective view of a 30 terminal conforming portion.

Figure 4 is a section on line 4—4 of Figure 1.

Figure 5 is a perspective view of the separator.

35 Figure 6 is a perspective view of one of the vanes hereinafter described.

Figure 7 is a fragmentary section on line 7—7 of Figure 4.

Figure 8 is a fragmentary section on line 40 8—8 of Figure 4.

Figure 9 is a side view, showing the two fluid-directing plates assembled.

Figure 10 is a section on line 10—10 of Figure 1, as seen from the intake end, parts 45 shown by Figure 1 being omitted.

Figure 11 is a section on line 11—11 of Figure 1, as seen from the outlet end.

Figure 12 is a section through the synchronizing gear shaft axis, as seen from the 50 intake end.

Figure 13 is a perspective view, showing separably the sectional shaft carrying a fluid-directing plate.

Figure 14 is a view somewhat similar to

Figure 1, but showing a modified construction. 55

Figure 15 is a top plan partly in section of the same construction.

Figure 16 is a longitudinal section through a relief valve. 60

Figure 17 is a section on line 17—17 of Figure 16.

The same reference characters indicate the same parts in all of the figures.

Referring to Figures 1 to 13, the casing 65 of my improved mechanism provides a fluid conduit including reduced terminal portions

12, 12, one of which constitutes a fluid intake, and the other a fluid outlet. The casing is preferably of sectional construction, 70 as shown by Figures 1 and 4, the terminal portions 12 being flanged, and preferably rectangular in cross section, and connected by bolts 15 to flanged conforming portions, or adapters, shown by Figures 1 and 3. 75 Each of the adapters here shown indicates a rectangular flange 12^a, coupled to a rectangular flange on a terminal portion 12, a circular flange 12^b, adapted to be coupled to a circular flange on a cylindrical conduit section, not shown, forming a part of a pipe line, and an intermediate conduit portion 12^c.

The casing is enlarged between the terminal portions 12, and includes curved wall 80 portions 13, 13, which if connected or extended, as indicated, by the dotted line x—x in Figures 1 and 1^a, would constitute segments of an ellipse, bisected by the major axis of the ellipse. I therefore call the portion of the casing which includes the wall 85 portions 13 an elliptical enlargement of the casing, the function of which will appear hereinafter.

The casing may be constructed in flanged half sections as at 131 and 132 in Figure 12 bolted together. The upper wall portion 13 is preferably separable from the body or main portion of the casing, to permit access to the interior of the latter, and is formed as a part of a cover section 13^a, which is flanged and secured by bolts 14 to the flanges formed on the body of the casing. 90

Within the said elliptical enlargement is a fixed elliptical separator 16, forming inner walls of two channels 17, the outer walls of which are formed by the wall portions 13. 95 The separator is separably secured to the 100 105

casing, preferably by the means hereinafter described, and its major axis is substantially at right angles with the major axis of the elliptical enlargement of the casing, so that 5 the channels 17 are of varying width, as shown by Figures 1 and 1^a. The elliptical enlargement includes side walls 13^b, having offset portions 13^c, forming circular recesses or housings, one elevated above the other, as 10 shown by Figure 4. In each of the housings is located a shroud wheel, each designated as a whole by the reference numeral 18 in Figure 4, the wheel in the upper housing being called the upper shroud wheel, and the other 15 the lower shroud wheel. Said wheels approximately fill the housings, and their inner sides are substantially flush with the main portions of the side walls 13^b, so that fluid passing through the elliptical enlargement is 20 guided in part by the shroud wheels, and in part by the said main portions.

Each shroud wheel is fixed to a shaft 19, which is journaled in fixed bearings herein-after described, supported by the casing, the 25 shafts projecting outward from the outer sides of the wheels. The shaft of the upper shroud wheel is concentric with the upper wall portion 13 of the elliptical casing enlargement, and the shaft of the lower shroud 30 wheel is concentric with the lower wall portion 13.

Fixed to and projecting from the inner side of each shroud wheel is a series of cantilever pins 20.

35 The mechanism includes a series of elongated vanes 21, having sockets 22 in their end portions. Each vane is preferably of the flattened or elliptical form shown by Figures 1, 1^a and 6, and each is pivotally connected with the two shroud wheels by said pins and sockets, one end of each vane being thus connected with the upper shroud wheel, and the other end with the lower shroud wheel.

40 23 represents an elongated synchronizing shaft, parallel with the wheel shafts 19, and journaled in fixed bearings, 24 (Figure 12).

One end portion of the synchronizing shaft is provided with a gear 25 (Figures 1, 50 4, 7 and 12), meshing with a smaller gear 26 on the shaft 19 of the upper shroud wheel. The opposite end portion of the synchronizing shaft is provided with a gear 25^a (Figures 4, 8 and 12), meshing with a smaller gear 26^a on the shaft 19 of the lower shroud wheel. The arrangement is such that the vanes 21 have an orbital movement in the channels 17, and are maintained with their major axes parallel with each other, and 55 substantially at right angles with the path of fluid flowing through the channels, so that each vane presents a broad side to the fluid, as indicated by Figures 1 and 1^a.

60 The casing is provided with fluid guiding or deflecting means, as hereinafter described,

whereby fluid may be caused to pass wholly at one side of the separator 16, and through only one of the channels 17, so that the vanes in one channel are active, while those in the other channel are inactive.

70 The shroud wheel shafts 19 are preferably tubular, and cooperate with the means next described for detachably securing the separator 16 in its operative position. I have embodied said means in rods 27, screw-threaded at their inner ends, and engaged with tapped sockets 28, in the separator. Said rods extend through the hollow wheel shafts 19, and through glands 29, secured by bolts 29^a (Figure 1) to the outer ends of 80 said shafts, and rotating with the latter on the rods 27. The outer ends of the rods 27 are rigidly connected with the fixed supports, to prevent rotation of the rods, by pins 30 passing through the rods, and arms 31 fixed to said supports and engaged with the pins 31, as shown by Figures 1 and 4. The said fixed supports are preferably uprights 50, forming portions of two extensions projecting laterally from the central portion of the casing, as shown by Figure 4. Said uprights are provided with outer bearings 32, for the wheel shafts 19.

85 Said shafts are provided at opposite sides of the bearings 32 with collars 19^a. Inner bearings for the wheel shafts 19 are provided by hollow bosses 35, fixed to and projecting outward from the central portion of the casing, and glands 34 secured by bolts 34^a (Figure 1) to said bosses, and securing packing at 34^b. Packing is also secured at 34^c by the glands 29.

90 For combined lightness and strength each shroud wheel is preferably composed of two spaced apart disks 18^a, a tubular hub 18^b, secured by its flanged ends to said disks, and suitably fixed to the wheel shaft, and tubular separators 18^c secured by their flanged ends to the disks, the cantilever pins 20 being 100 fixed in said separators.

105 The synchronizing shaft 23, and the gearing connecting the same with the shroud-wheel shafts 19, constitute the preferred embodiment of means for synchronizing the rotation of the shroud wheels and causing the vanes 21 to stand in parallel planes. I desire it understood, however, that any other suitable synchronizing means may be employed without departing from the spirit 110 of the invention.

115 I will now describe the preferred means for directing the fluid passing through the casing, so that it will flow through one of the passages 17, and will be excluded from the other.

120 40 represents a directing plate or gate, hinged within one end portion of the casing, and adapted to swing between stop shoulders 40^a, to deflect fluid entering the casing into one or other of the passages 17, the plate 125 130

- being adapted to be thrown into one or other of the two positions, shown by full and dotted lines in Figure 9, to suit the drive desired, be it right hand or left hand when used as a motor; and when used as a pump to suit rotation of the shroud-wheel vanes. The plate 40 has a hub at its inner edge, attached as by a pin 38^b to a two piece transverse shaft 38—38^a, which is journaled in bearings 13^g and 13^h (Figure 10) at opposite sides of the casing. The bearing 13^g is closed by a cap 36. The bearing 13^h is an element of a stuffing-box, and has a packing-confining gland 37.
- 10 To the projecting end of the shaft is fixed as by a nut 43, a crank arm 42, whereby the plate 40 may be swung from one operative position to the other. The plate 40 projects in only one direction from its hub, and is therefore called a one-armed directing-plate.
- 15 39 represents a directing-plate or gate hinged within the opposite end portion of the casing and adapted to swing between stop shoulders 39^a to guide fluid to the casing outlet after it has passed through one passage 17, and prevent back flow of the fluid through, or into the other passage. The plate 39 has a hub midway between its ends attached to a shaft 38, which is paired 20 with the shaft 38^a, both being journaled in bearings similar to those of the shaft 38—38^a as shown by Figures 10 and 11. The plate 39 projects in opposite directions from its hub, and is called a two-armed directing-plate. A crank arm 42^a fixed to the shaft 38^a, enables the plate 39 to be swung from either of the positions shown by full and dotted lines in Figure 9, to the other position.
- 25 40 A biasing weight 46 attached to the crank arm 42^a is adapted to hold the two-armed plate 39 in either of its operative positions. When the plate 39 is in the full line position, its inner arm directs fluid from the lower passage 17 to the outlet end of the casing, and its outer arm prevents back flow of the fluid to, or toward the upper passage 17. To enable the directing plates to be swung in unison, I provide a connecting rod 48, secured at one end by a yoke piece 45 to the crank arm 42, and by a pin 49 to the weight 46.
- 30 Each of the director plate shafts is preferably composed of two separable sections to aid assembling as shown separately by Figure 13, the inner end of one section having a tongue 38^a, and the inner end of the other section a tongue-receiving groove 38^c. One of the sections has an enlargement 38^d, confined by the cap 36 in an enlargement of the bearing 13^g.
- 35 The casing is provided with a fixed crossbar 51, having a curved outer edge fitting the hub of the plate 40, as shown by Figure 2, and a curved edge face 51^a, which is a segment of the ellipse defined in part by the dotted lines *x* (Figures 1 and 1^a). Said crossbar is formed to cooperate with the plate 40 in directing fluid into either of the passages 17, and is bored to permit the passage of the shaft 23 through it.
- 40 The casing is also provided with a fixed crossbar 53, formed to arrest either of the arms of the plate 39, when said plate is in an operative position, and provided with a curved edge face 53^a, which is another segment of said ellipse.
- 45 It might sometimes happen through wear of the parts, or other cause, that the fluid might leak into the inactive passage of the mechanism and being trapped therein would create back pressure. In order to prevent such action the inactive passage of the channel may be provided with a relief passage opening to the tail race. As either passage may be inactive the opposite side being active, depending on the manner in which the directing vanes are positioned, connection to the tail race is provided from both branches of the fluid channel, a valve being 50 interposed therein movable to close that passage extending from the active branch at any time while leaving the other branch or passage open. This is disclosed in Figures 1, 4, 9 and 14 to 16 inclusive. Referring to these figures, pipes as 54^e and 54^d, extend from ports 54^e and 54^f opening into the upper and lower channels, respectively, and communicating with a valve casing 65 from which leads a pipe 54^g extending to the tail race. The valve casing 65 has therein a pair of aligned directing vanes 390, as shown in Figures 16 and 17, which may be positioned as shown in full lines in Figure 16, so that the vanes close off the pipe 54^d from the outlet 54^e while opening the pipe 54^e thereto, or these vanes may be turned so that they close off the pipe 54^e while the pipe 54^d is open to the exhaust pipe 54^g. The full line position is shown in Figure 16 with the pipe 54^e open to the tail race so that the upper passage is vented while the lower passage communicating with the pipe 54^d is closed off. This corresponds to the position of the parts when the lower passage is active as shown in Figure 14. When it is desired to reverse the direction of the impelling mechanism by directing the flow through the upper passage, the directing plates 39 and 40 are thrown over to direct the fluid through the upper passage as heretofore described. When this is done the upper port 54^e should be closed off from the tail race, while the lower port 54^f should be open thereto. This may be done by reversing the directing vanes within the valve casing 65 and in order that it may be done in time with the reversals of the flow directing plates 39, and 40, connection may be made therefrom to the actuating mechanism for these directing plates.
- 55 60 65 70 75 80 85 90 95 100 105 110 115 120 125 130

As shown this comprises an arm 42^b fixed to the shaft 38ⁱ and 38^k on which the vanes 390 are carried, this arm 42^b being pivoted to a link 58^a extending to the operating arm of connecting rod 48. When this connecting rod is thrown to either of its positions the directing vanes 390 are therefore also thrown in a corresponding manner, as is shown in Figure 9.

- 10 In Figure 1 a slight modification of the position of valve 65 has been indicated, in this construction the link 58^a being fixed to the counterweight 46 rather than extending to the intermediate coupling 59, as shown in Figure 9. The action, however, is the same in both cases.

In Figures 14 and 15 a modified construction of the synchronizing mechanism has been indicated. In these figures the shroud 20 wheels 55 and 55^a have peripheral teeth thereon which mesh with pinions 260 carried by the equalizing shaft 23. The synchronizing means in this instance is thus entirely enclosed within the machine casing 25 and eliminates the necessity of the gears 26 and 26^a illustrated in Figures 7 and 8 outside of the machine housing. Two cover plates 56 and 57 may be positioned on opposite sides of the casing to permit the ready 30 removal and replacement of the rotor. Otherwise this construction is substantially the same as that illustrated in the other figures.

When the described mechanism is used as 35 a motor, the impelling fluid may be either liquid or gaseous and the intake end of the casing will preferably be that having the single director plate 40, this plate and the two-armed director plate 39 enable the 40 direction of rotation of the rotor provided by the shroud wheels and vanes to be reversed by varying the positions of said plates, as indicated by full and dotted lines in Figure 9. It will be noted 45 also that the vent ports are on the side of the rotor axis adjacent to the intake end of the casing.

When the mechanism is used as a pump, the rotor being driven by a suitable motor, 50 either end of the casing may be conveniently used as the intake end. If the intake is at the end having the two-armed director plate 39 and the direction of rotation of the rotor is reversed when the plate 39 is in the 55 position shown by Figures 1 and 14, and by full lines in Figure 9, said two-armed plate will be automatically shifted by the suction exerted by the rotor, to the position shown by dotted lines in Figure 9, the director 60 plate 40 being automatically shifted at the same time through the described connections. The director plates may also be automatically shifted from the dotted line to the full line positions. The mechanism may be used 65 as a pump for either liquid or gaseous fluid,

and may be used to force the fluid in either direction, though the vent ports should be positioned adjacent to the suction end and lead to the suction side of the directing vanes so that any fluid leaking into the inactive portion would find its way back to the suction side without causing back pressure.

It will be noted that the elliptical contours of the vanes in the plane of their path of motion, which is also elliptical, cause them to engage the outer face of the separator 16 and the inner wall of the casing throughout nearly the entire periods when they are passing into and out of the active fluid channel, thus substantially sealing them against the entrance and exit walls of this channel as they pass therethrough. This avoids the trapping of fluid back of the vanes as they leave the fluid channel with the possibility of back pressure thereon. The fluid is thus permitted to pass through the mechanism with a steady flow substantially undisturbed by eddies or back pressure volumes and each of the vanes when 90 entirely within the channel closes it transversely and so is effective in transmitting to or receiving energy from the flow. Any leakage past the vanes is taken care of by the vents 54^e and 54^f which, of course, might 95 be made through the curved peripheral walls of the casing rather than through its ends, as shown, if desired.

It is obvious that the rotor composed of the shroud wheels, the vanes and the synchronizing means, may be employed as a motor, with a conduit adapted to conduct a fluid only at one side of the axis of the rotor, such, for example, as may be provided by omitting the upper channel 17 and the director plates, in which case the vanes will be acted on only by fluid passing through the lower channel 17, and it is also obvious that the mechanism might be arranged with its shroud wheel shafts vertical or at any desired 105 inclination.

Many other changes and modifications might also be made without departing from the spirit and scope of this invention.

I claim:

1. An impelling mechanism comprising a rotor composed of an upper shroud wheel having a shaft journaled in fixed bearings, a lower shroud wheel having a shaft journaled in fixed bearings and parallel with the shaft of the upper wheel, elongated vanes each pivotally connected at its upper end with the upper wheel, and at its lower end with the lower wheel, means for synchronizing the rotation of said wheels, and a fluid conduit arranged in the path of the vanes at one side of the axis of the rotor, the arrangement being such that the vanes have an orbital movement and are maintained with their major axes parallel with each other 120

115

125

130

- and substantially at right angles with the path of fluid in said conduit.
2. An impelling mechanism substantially as specified by claim 1, the pivotal connections between the said shroud wheels and the vanes being embodied in cantilever pins fixed to and projecting inwardly from the wheels, and sockets or bearings in the end portions of the vanes in which said pins are 10 adapted to turn.
3. An impelling mechanism substantially as specified by claim 1, each shroud wheel being composed of two spaced apart disks, a tubular hub secured at its ends to said disks, 15 and fixed to the wheel shaft, tubular separators secured at their ends to said disks, and cantilever pins fixed to said separators and projecting from the inner side of the wheel, said pins being journaled in sockets in end 20 portions of the said vanes.
4. An impelling mechanism comprising a casing forming a fluid conduit, having intake and outlet end portions, and an intermediate enlargement including curved wall 25 portions, forming segments of an ellipse, the major axis of which is perpendicular to the path of fluid passing through the conduit; an elliptical separator, means securing the separator within said enlargement, with its 30 major axis substantially at right angles with the major axis of the ellipse of which said wall portions are segments, said separator and wall portions forming walls of two curved channels of varying width at opposite sides of the separator; an upper shroud 35 wheel having a shaft journaled in fixed bearings concentric with the upper curved wall portion of the enlargement, a lower shroud wheel having a shaft journaled in fixed bearings 40 concentric with the lower curved wall portion of said enlargement; elongated vanes, each pivotally connected at one end with the upper wheel, and at its other end with the lower wheel, and means for synchronizing the rotation of the shroud wheels, 45 the arrangement being such that the vanes have an orbital movement in said channels, and are maintained with their major axes parallel with each other, and substantially 50 at right angles with the path of the fluid.
5. An impelling mechanism substantially as specified by claim 4, means being provided for directing fluid through either of said channels, and excluding it from the other 55 channel.
6. An impelling mechanism substantially as specified by claim 4, means being provided for directing fluid through either of said channels and excluding it from the other channel, said means being automatically 60 shiftable to automatically change the flow of fluid from one channel to the other.
7. An impelling mechanism substantially as specified by claim 4, the said enlargement 65 being provided with side walls having offset portions forming circular housings for said shroud wheels, the inner sides of the shroud wheels being substantially flush with the main portions of the side walls, so that fluid passing through the enlargement is guided 70 in part by the shroud wheels, and in part by said main portions.
8. An impelling mechanism substantially as specified by claim 4, the shroud-wheel shafts being tubular, and provided with 75 glands, and the separator-securing means being embodied in rods fixed at their inner ends to the separator, and extending through the hollow shafts and glands.
9. An impelling mechanism substantially 80 as specified by claim 4, the shroud-wheel shafts being tubular, and provided with glands, and the separator-securing means being embodied in rods fixed at their inner ends to the separator, and extending 85 through the hollow shafts and glands, and rigid connections between the outer ends of said rods and the casing.
10. An impelling mechanism substantially 90 as specified by claim 4, the said casing comprising a central portion which includes said conduit, inner wheel shaft bearings supported by said central portion, lateral extensions at opposite sides of the central portion, and outer wheel shaft bearings supported by said 95 extensions.
11. An impelling mechanism substantially 100 as specified by claim 4, the said casing comprising a central portion which includes said conduit, inner wheel shaft bearings supported by said central portion, lateral extensions at opposite sides of the central portion, and outer wheel shaft bearings supported by said 105 extensions, said inner bearings being formed as stuffing boxes.
12. An impelling mechanism comprising 110 a casing forming a fluid conduit, having intake and outlet end portions, and an intermediate enlargement including curved wall portions forming segments of an ellipse, 115 the major axis of which is perpendicular to the path of fluid passing through the conduit; and elliptical separator, means securing the separator within said enlargement with its major axis substantially at right 120 angles with the major axis of the ellipse, of which said wall portions are segments, said separator and wall portions forming walls of two curved channels of varying width at opposite sides of the separator; an upper 125 shroud wheel having a shaft journaled in fixed bearings concentric with the upper portion of the enlargement, a lower shroud wheel having a shaft journaled in fixed bearings concentric with the lower portion of said enlargement, elongated vanes, each pivotally connected at one end with the upper wheel, and at its lower end with the lower wheel; a synchronizing shaft; and gears connecting the wheel shafts with the syn- 130

chronizing shaft, the arrangement being such that the vanes have an orbital movement in said channels, and are maintained with their major axes parallel with each other, and substantially at right angles with the path of the fluid.

13. An impelling mechanism substantially as specified by claim 4, the portion of the casing which includes one of said curved 10 wall portions being removable and detachably secured to the body of the casing to permit access to the interior of the casing.

14. An impelling mechanism substantially as specified by claim 4, the end portions 15 of the casing being angular in cross section, and provided with detachably secured extensions, each angular at its inner end to conform to an angular end of the casing, and circular at its opposite end to conform to 20 a cylindrical conduit section.

15. An impelling mechanism substantially as specified by claim 4, comprising also hinged fluid-directing plates within the end 25 portions of the casing, adapted to cause the passage of fluid through either of said channels, and means external to the casing for swinging said plates, the casing being provided with stops adapted to support said plates in different positions.

30 16. An impelling mechanism substantially as specified by claim 4, comprising also hinged fluid directing plates within the end portions of the casing adapted to cause the 35 passage of fluid through either of said channels, and connections between said plates causing them to swing in unison, the casing being provided with stops adapted to support said plates in different positions.

17. An impelling mechanism substantially 40 as specified by claim 4, comprising also hinged fluid directing plates within the end portions of the casing adapted to cause the 45 passage of fluid through either of said channels, and connections between said plates causing them to swing in unison, the casing being provided with stops adapted to support said plates in different positions, one 50 of said plates having two arms and being arranged to be automatically shifted and to shift the other plate through said connections.

55 18. An impelling mechanism substantially as specified by claim 4, comprising also hinged fluid-directing plates within the end portions of the casing, adapted to cause the 60 passage of fluid through either of said channels, crank arms connected with said plates outside the casing, and connections between said crank arms whereby the said plates may be simultaneously swung, the casing being provided with stops adapted to support said plates in different positions.

65 19. An impelling mechanism substantially as specified by claim 4, comprising also a one-armed fluid-directing plate hinged

within the intake end portion of the casing, and formed to deflect fluid into either of said channels, a two-armed fluid-directing plate hinged within the outlet portion of the casing, and formed to direct fluid from one of 70 said passages, and prevent back flow of the fluid into the other passage, crank arms connected with said plates outside the casing, and connections between said crank arms whereby the plates may be simultaneously 75 swung, the casing being provided with stops adapted to support said plates in different positions.

20. An impelling mechanism substantially as specified by claim 4, comprising also 80 a one-armed fluid-directing plate hinged within the intake portion of the casing, and formed to deflect fluid into either of said channels, a two-armed fluid-directing plate hinged within the outlet portion of the casing, and formed to direct fluid from one of 85 said passages, and prevent back flow of the fluid into the other passage, crank arms connected with said plates outside the casing, and connections between said crank arms whereby the plates may be simultaneously 90 swung, the casing being provided with stops adapted to support said plates in different positions, the said connections including a 95 biasing weight whereby the said plates are confined in either of the positions to which they may be swung.

21. An impelling mechanism comprising a series of vanes held in parallel relation and movable in an elliptical path, of a casing 100 enclosing said vanes and defining a fluid channel substantially closed transversely by said vanes throughout one portion of their path and defining lateral openings through which said vanes enter and leave said channel at opposite ends of said portion, said vanes being of elliptical cross section in the plane of their path to substantially close 105 said openings during their passage therethrough.

22. An impelling mechanism comprising a series of vanes held in parallel relation and movable in an orbital path, of a casing defining a fluid channel conforming to a portion of said path through which said vanes 110 pass, and defining lateral openings to said channel through which said vanes pass into and out of said channel, said vanes being of such cross sectional contour relative to their path of motion as to substantially close such openings during their time of travel therethrough.

23. An impelling mechanism comprising a series of vanes held in parallel relation and movable in an orbital path, of a casing defining a fluid channel conforming to a portion of said path through which said vanes pass and substantially closed transversely by each of the vanes therein, and defining lateral openings to said channel 125 130

through which said vanes pass into and out of said channel, said vanes being of such cross sectional contour relative to their path of motion as to substantially close such openings during their time of travel therethrough.

24. An impelling mechanism comprising a rotor composed of a pair of shroud wheels journaled for rotation on parallel axes, vanes each pivotally connected at opposite ends to said wheels, means for synchronizing the rotation of said wheels, and a fluid conduit arranged in the path of the vanes at one side of the axis of the rotor, the arrangement being such that the vanes have an orbital movement and are maintained with their major axes parallel with each other and at right angles to the path of fluid in said conduit.

25. An impelling mechanism comprising a rotor composed of a pair of shroud wheels journaled for rotation on parallel axes, vanes each pivotally connected at opposite ends to said wheels, means engageable with the peripheries thereof for synchronizing the rotation of said wheels, and a fluid conduit arranged in the path of the vanes at one side of the axis of the rotor, the arrangement being such that the vanes have an orbital movement and are maintained with their major axes parallel with each other and at right angles to the path of fluid in said conduit.

26. An impelling mechanism comprising a rotor composed of a pair of shroud wheels journaled for rotation on parallel axes, vanes each pivotally connected at opposite ends to said wheels, means for synchronizing the rotation of said wheels, a fluid conduit arranged in the path of the vanes on each of opposite sides of the axis of the rotor, said conduits merging at either end, and plates movable to direct fluid to either of said conduits and to close off the other conduit, the arrangement being such that the vanes have an orbital movement and are maintained

with their major axes parallel with each other and at right angles to the path of fluid in said conduit.

27. An impelling mechanism comprising 50 a rotor composed of a pair of shroud wheels journaled for rotation on parallel axes, vanes each pivotally connected at opposite ends to said wheels, said wheels having peripheral gear teeth, a shaft having pinions 55 fixed thereto meshing with the teeth of said shroud wheels to effect simultaneous synchronized movement of said wheels, a fluid conduit arranged in the path of the vanes on each of the opposite sides of the axis of 60 the rotor, said conduits merging at either end, and plates movable to either of said conduits and to close off the other conduit.

28. An impelling mechanism comprising 65 a casing shaped to define a pair of passages, a series of impeller vanes mounted to travel in a closed path passing through said passages on opposite portions thereof, means for directing fluid through either of said passages to determine the relative directions 70 of travel of fluid flow, and means for venting the passages closed off to permit the escape of leakage therefrom.

29. An impelling mechanism comprising 75 a casing shaped to define a pair of passages spaced apart at said ends, a series of impeller vanes mounted to travel in a closed path and passing through said passages at opposite portions of said path, fluid-directing plates movable to direct the fluid to either of 80 said passages at will, and to exclude vent ports leading from said passages to a point beyond the directing plates in the direction of the flow of the fluid, and means controlled by said directing plates for opening 85 the port leading from that passage from which the fluid is excluded and into which the fluid is directed.

In testimony whereof I have affixed my signature.

JAMES EDGAR BORDEN.
